WELL PUMPING APPARATUS INVOLVING A
SUCKER ROD

Edgar W. Mong, Los Angeles, Calif.

Application January 15, 1947, Serial No. 722,280

12 Claims. (Cl. 103—206)

1

This invention has to do with well pumping apparatus involving a sucker rod and it is a general object of the invention to provide in such apparatus load supporting means in connection with the rod operable to support a portion of the weight or load on the rod.

Piston and cylinder type pumps operated by rods are generally most satisfactory for pumping oil wells. However, such equipment as ordinarily used has certain limitations and the depth of operation is limited. The principal limitation on such equipment is due to the weight and stretch of the rods. As depths increase the weight of the column of fluid above the pump increases and the weight and stretch of the string of rods increases. As a result of such conditions a point is reached where it is impractical to attempt to operate a pump since movement imparted to the rods at the surface of the well is largely, if not completely, absorbed before reaching the pump. Furthermore, as the weight of the rods increases the strain on the rods increases, adding to the hazards of operation.

It is an object of the present invention to provide a simple, practical arrangement and combination of parts whereby a sucker rod is handled in a deep well so that the strains due to the weight of the rod are effectively reduced making it possible to successfully operate a pump at a great depth.

Another object of the invention is to provide an attachment applicable to standard well equipment such as a standard sucker rod and a standard pump, without appreciable alteration thereof.

It is another object of the invention to provide an attachment acting between a fixed point in the well tubing and a point on the rod intermediate its ends to relieve strains due to loads on or the weight of the rods.

Another object of the present invention is to provide a resilient element such as a spring or the like interposed between the tubing and rod acting between a support in the tubing and a stop on the rod which stop is adjustable lengthwise of the rod to bring the parts into the desired working relationship.

It is another object of the present invention to provide an attachment of the general character referred to which is such that the bulky parts occupying appreciable space between the tubing and rod are removable with the rod making it possible to remove the pump or parts of the pump by means of the rod in the usual manner.

The various objects and features of my inven-

2

tion will be fully understood from the following detailed description of typical preferred forms and applications of the invention, throughout which description reference is made to the accompanying drawings, in which:

Fig. 1 is a view of a typical well and pumping equipment application thereto including the structure of the present invention. Fig. 2 is an enlarged longitudinal sectional view of the equipment in the well showing the structure provided by the present invention being an enlarged view taken as indicated by line 2—2 on Fig. 1. Fig. 3 is an enlarged plan section taken as indicated by line 3—3 on Fig. 2. Fig. 4 is an enlarged plan section taken as indicated by line 4—4 on Fig. 2. Fig. 5 is an enlarged detailed sectional view showing another form of construction provided by the present invention, and Fig. 6 is an enlarged longitudinal sectional view taken at the pump, illustrating the essential parts of a pump that may be used in carrying out my invention.

My present invention can be used under various working conditions. However, it is particularly useful as applied to or in connection with well pumping apparatus and particularly where a well pump is to be operated at great depths in a well. In the drawings I illustrate a typical well provided with the usual casing A and I show a derrick B at the top or head of the well. A typical or common type of pump operating mechanism is illustrated at the derrick, which mechanism involves, essentially, a walking beam 10 and a drive 11 therefor. A head 12 is provided at the upper end of the well casing A and a tubing 13 is carried by the head 12 and extends downwardly into the well to carry the pump C and to form a conduit for fluid handled by the pump. A flow line 14 is provided at the derrick to handle flow from the tubing and a sucker rod D extends downwardly through the tubing to operate the pump. The sucker rod D involves a plurality of rod sections 15 joined end to end by suitable couplings 16 in the manner common to sucker rods used for operating well pumps. The upper end of the sucker rod includes a finish section or polish rod 17 by which the sucker rod is joined to the walking beam 10. The polish rod 17 operates through a suitable stuffing box 18 or the like.

My present invention provides, primarily, a resilient element arranged between the tubing 13 and the rod D which element is preferably a helical spring. In the drawings I show the resilient element as a helical spring 20, the lower

end of which is carried by a seat in the tubing while the upper end engages a stop on the sucker rod. The spring 20 is a compression spring of substantial length and its convolutions are so spaced as to allow its upper end to move through the full or desired stroke while its lower end remains stationary or fixed.

The support provided in the tubing 13 is located at a suitable point between the pump C and the head of the well, and in practice it may vary considerably in form and construction as will be apparent from an examination of Figs. 2 and 5 of the drawings. In the form of the invention illustrated in Fig. 2 of the drawings the support involves a seat ring 21 fixed in the tubing to project inwardly from the inner wall 22 of the tubing, so that it presents an upwardly facing shoulder 23 forming a rest for the lower end of the spring. In this case the support is formed entirely of one part, that is, of the ring 21 and the ring is fixed in position in the tubing, being located within a coupling 24 of the tubing string so that it is confined between the ends of adjacent tubing sections 25. In practice it is preferred to form the ring 21 so that it projects radially inward from the tubing just far enough to form a suitable shoulder 23 for supporting the spring 20 and if desired the tubing, seat ring 21 and pump or pump parts can be related so that the pump or pump parts may be inserted into the well or withdrawn therefrom through the seat ring.

In the form of the invention illustrated in Fig. 5 of the drawings the support involves a removable seat ring 21^a on which the spring 20 rests and a shoulder ring 30 carried by the tubing and having an upwardly facing shoulder 31 on which the ring 21^a is supported. The seat ring 21^a is proportioned to slidably fit within the tubing 13 and the shoulder ring is proportioned to project inwardly from the interior of the tubing far enough to effectively support the seat ring, as shown in Fig. 5 of the drawings. The opening 32 through the ring is preferably made as large as possible so that the shoulder ring will readily pass a pump or pump parts in the course of their being lowered into or withdrawn from working position. The seat ring illustrated in the drawings is provided with an upwardly facing recessed shoulder 23^a receiving and holding the lower end of the spring 20. When this form of construction is employed the seat ring is proportioned so that the opening 35 provided therethrough to pass the sucker rod D is proportioned to pass the sucker rod with substantial clearance but will not pass the pump or pump parts. With the construction just described the seat ring 21^a is applied to the sucker rod above the pump or pump parts and as the pump or pump parts are withdrawn they engage the seat ring and lift it from the shoulder ring so that the seat ring and spring are withdrawn from the well with the sucker rod.

The pump C may be any ordinary well pump of the type to be operated by a rod. For instance, it may be either the working plunger type or the work barrel type. In Fig. 6 of the drawings I illustrate, generally, a pump of the working plunger type in which the standing valve body 70 is releasably held at the lower end of the tubing 13 by a suitable pump anchor 71 while the plunger 72 is designed to reciprocate in the barrel 73 and is coupled to the lower end of the rod D. In accordance with the broader principles of my invention I contemplate that either a part of the pump such as the plunger 70 or whichever part is directly attached to the rod D, or possibly the pump as a

whole, may be removable from the well through the tubing as the rod D is removed. If the entire pump is removable the form of the invention illustrated in Fig. 5 can be used to advantage as the opening 32 in the shoulder ring 30 may be easily made large enough to readily pass the entire pump, that is, the assembly of the barrel 73 and plunger 72. If the pump is such that only a part such as the plunger 72 is removed with the rod D the opening at the seat need not be large, in which case I can employ the form of the invention illustrated in Fig. 2. However, it is to be understood that I may, in certain cases, be able to remove the entire pump through the seat ring 21 as shown in Fig. 2 where the relative size of the tubing and pump permit of this construction.

The stop provided on the sucker rod to be engaged by the upper end of the spring may be any suitable projection on the rod against which the spring may bear upwardly. In the drawings I have shown a stop applicable to the sucker rod at any desired point along its length making it possible to so locate the stop to work in the most advantageous manner relative to the support that carries the lower end of the spring.

The particular stop illustrated in the drawings is in the nature of a collar 40 applied to a rod section 15 at the desired point lengthwise of the sucker rod. The collar is preferably split longitudinally so that it involves sections 41 which sections may be advantageously joined by suitable fastening means such as bolts 42. The sections may be like opposed sections such that when the bolts 42 are tightened the collar is made fast on the rod section so that it will not move lengthwise thereof. In practice I may provide anti-friction means on the collar 40 so that the collar will not cause excessive wear of the tubing as it works up and down therein. In the particular case illustrated I show the collar provided with circumferentially spaced peripheral sockets 50 carrying rollers 51 that are supported on suitable supporting pins 52. The rollers are so mounted as to project somewhat radially from the roller and in practice they may be crowned, as shown in Fig. 3 of the drawings, to conform to the configuration of the interior 22 of the tubing in which they operate.

In applying my present invention I may use one or more springs 20 in connection with a single sucker rod D, that is, if I desire I may locate several springs at suitable intervals within the tubing 13. It will be apparent that a spring 20 such as I have provided resting on a support 55 in the tubing and engaging a stop on the rod will serve to resiliently support the rod as weight of the rod or load applied through the rod is allowed to be borne by the spring. The structure that I have provided acts to center the rod in the tubing and to hold the rod under tension so that it is straight. By holding the rod straight in the tubing wear on the rod and on the wall of the tubing is minimized. In practice each spring 20 is so located that as the rod D reciprocates in the course of operating the pump C it alternately contracts and expands, its range of movement being such as to allow for full travel or operation of the rod in order to gain the desired action or operation of the pump.

In a typical installation I may proportion the spring 20 as to length and strength or, if necessary, I may employ enough springs 20 so that under normal working conditions the load on the sucker rod and the weight of the rod itself is such as to compress the spring or springs so

that the load and weight combined assure operation of the pump parts to the down or lowered position. As the rod is moved up through operation of the walking beam or other actuating mechanism the operating mechanism does not have to lift the entire weight of the rod together with the load imposed thereon, but rather lifts only part of this weight and load as the spring or springs being under compression exert upward force on the rod. By proper design and proportioning the upward force exerted by the spring or springs may be substantial, with the result that a substantial amount of the upward strain is taken by the spring or springs and since the springs are located to engage the rod intermediate its ends the entire weight and load is not concentrated on the upper end portion of the rod as it ordinarily is, but is distributed so that the equipment will work satisfactorily at greater depths than it would if not equipped with the spring or springs of the present invention.

Employing the present invention as hereinabove described it will be apparent that load or strain ordinarily communicated by the rod to the head of the well is communicated from the rod to the tubing at one or more points in the well. Where the tubing is such that it may stretch or work as a result of the forces or loads applied thereto through the spring or springs it may be desirable to provide anchoring means for the tubing so that the forces or strains tending to move or work the tubing are communicated to the casing, which is ordinarily so mounted and anchored as to provide an effective or positive support. In the drawings I have shown a simple anchor 60 acting between the tubing 13 and the casing A so that load or downward force that would otherwise tend to move or stretch the tubing is communicated to the casing so that the tubing affords a fixed or immovable support for the lower end of the spring which is taking part of the load or weight of the sucker rod.

Certain structural elements that I have disclosed in this application are employed in the structure which is the subject of my copending application entitled "Well Pumping Apparatus" filed January 15, 1947, Serial No. 722,279.

Having described only typical preferred forms and applications of my invention, I do not wish to be limited or restricted to the specific details herein disclosed, but wish to reserve to myself any variations or modifications that may appear to those skilled in the art and fall within the scope of the following claims:

Having described my invention, I claim:

1. An attachment for a well tubing with a rod extending therethrough and having a part at its lower end carrying a pump element including, a seat supported in the tubing below its upper end, a sectional stop clamped to the rod within the tubing, and a helical spring confined between the seat and stop, the clamp being selectively positioned on the rod above the said part.

2. An attachment for a well tubing with a rod extending therethrough including, a seat supported by the tubing below its upper end, a sectional stop clamped to the rod within the tubing, anti-friction members carried by the stop and engaging the interior of the tubing, and a helical spring within the tubing surrounding the rod and confined between the seat and stop.

3. An attachment for a well tubing having sections joined by a coupling and a rod in the tubing including, a seat supported by the tubing,

a stop supported by the rod, and a helical spring confined between the seat and stop, the seat including a fixed member held in the tubing within the coupling and between the sections and a part separate from and resting on said member and engaged by the spring and removable from the tubing by means of the rod.

4. An attachment for a well tubing and a rod extending therethrough including, a seat applicable to the tubing, a stop applicable to the rod, and a helical spring confined between the seat and stop, the seat including a member fixed in the tubing and a part resting on said member, engaged by the spring and removable from the tubing by means of the rod, the stop including separable sections and means operable to clamp the sections on the rod.

5. An attachment for a well tubing with a rod extending therethrough including, a seat applicable to the tubing, a stop applicable to the rod, and a helical spring confined between the seat and stop, the seat including a shoulder ring applicable to the tubing to be held in a fixed position in the tubing and a seat ring slidable in the tubing resting on the shoulder ring and engaged under the spring.

6. In combination, a tubing, a pump releasably supported at the lower end of the tubing, a rod extending through the tubing and attached to the pump, a stop fixed on the rod within the tubing, a seat in the tubing below the stop, and a spring in the tubing under compression between the stop and seat, the seat including a ring supported in the tubing against downward movement therein and having a shoulder engaged by the spring, the seat having an opening passing parts of the pump.

7. In combination, a tubing, a pump releasably supported at the lower end of the tubing, a rod extending through the tubing and attached to the pump, a sectional stop clamped to the rod within the tubing, a seat in the tubing below the stop, and a spring in the tubing under compression between the stop and seat, the seat including a ring applicable to the tubing to be held in a fixed position in the tubing and having a shoulder engaged by the spring, the opening through the ring passing pump parts operable through the tubing by the rod.

8. In combination, a tubing, a pump releasably supported at the lower end of the tubing, a rod extending through the tubing and attached to the pump, a stop on the rod, a seat in the tubing below the stop, and a spring in the tubing under compression between the stop and seat, the seat including a shoulder ring applicable to the tubing to be held in a fixed position in the tubing and a seat ring slidable in the tubing resting on the shoulder ring and engaged under the spring.

9. In combination, a tubing, a pump releasably supported at the lower end of the tubing, a rod extending through the tubing and attached to the pump, a stop on the rod, a seat in the tubing below the stop, and a spring in the tubing under compression between the stop and seat, the seat including a shoulder ring applicable to the tubing to be held in a fixed position in the tubing and a seat ring slidable in the tubing resting on the shoulder ring and engaged under the spring, the opening through the shoulder ring passing pump parts operable through the tubing by the rod.

10. In combination, a casing in a well, a tubing extending into the casing and having sections

joined by couplings, a pump carried in the well by the tubing at the lower end thereof, a rod extending into the tubing connected to and operating the pump, a seat in the tubing including a ring in the coupling and between adjacent tubing sections and a member separate from and resting on the ring, a sectional stop clamped to the rod within the tubing above the seat, a helical spring in the tubing surrounding the rod and under compression between the stop and said member, and means securing the tubing in the casing against movement by forces imparted to the tubing from the rod.

11. In combination, a casing in a well, a tubing extending into the casing and having sections joined by couplings, a pump carried in the well by the tubing at the lower end thereof, a rod extending into the tubing connected to and operating the pump, a seat in the tubing including a ring in a coupling and between adjacent tubing sections and a member separate from and resting on the ring, a stop on the rod above the seat, a helical spring in the tubing surrounding the rod and under compression between the seat and stop, and a releasable anchor securing the tubing in the casing against movement by forces imparted to the tubing from the rod.

12. In combination, a casing in a well, a tub-

ing extending into the casing, a pump carried in the well by the tubing, a rod extending into the tubing connected to and operating the pump, a seat fixed in the tubing, a stop clamped in fixed position on the rod above the seat, a helical spring in the tubing surrounding the rod and under compression between the seat and stop, and means securing the tubing in the casing against movement by forces imparted to the tubing from the rod, the opening through the seat passing parts of the pump movable through the tubing by means of the rod.
